ABSTRACT

A convection heat exchanger in which the fins of a fin-and-tube assembly each have U-shaped, spaced-apart edges which define a fin surface of a given area confined between lateral boundaries spaced-apart a distance smaller than the developed length of either edge.

FIG. 4.

CONVECTION HEAT EXCHANGER

BACKGROUND AND SUMMARY OF THE INVENTION

This invention relates in general to fin-and-tube type heat exchangers, and more particularly to a fin-and-tube assembly in which the fins have a special configuration that gives a more compact assembly for a given output rating.

In the prior art, fin-and-tube assemblies used in convection radiators had a plurality of heat exchanger tubes extending through a multiplicity of rectangular fins. These heat exchanger tubes were ordinarily parallel, located in a common plane elevated above the floor about seven inches. All tubes of the same assembly were manifold connected at each end, and plumbing connections to the manifolds were by pipes extended up through the floor.

The typical radiator unit has an enclosure which defined an air flow path from an inlet opening at the bottom to an outlet grill at the top. The fin-and-tube assembly within the enclosure was located as close to the bottom as permitted by the standard plumbing connections so as to maximize the natural draft effect obtainable with a given height of enclosure. This draft or chimney effect is determined by the difference in elevation between the fin-and-tube assembly and the hot air outlet, and in any case it is advantageous to increase the draft because the resultant increase in air flow past the fin-and-tube assembly gives better heat transfer with natural convection. Thus, for a given fin-and-tube assembly, a higher BTU heat output rating can be achieved by making the draft as high as possible.

In modern buildings, it is desirable in many cases to have radiator units that can be recessed flush into standard sized walls. Accordingly, it is advantageous to be able to make the fin-and-tube assemblies for such radiators as compact as possible, particularly in their depth dimensions.

The invention provides a fin-and-tube heat exchanger assembly for a convection type radiator that improves the overall heat transfer capability to the extent that a radiator unit of a given thermal capacity can be made more compact than would be possible using prior art designs.

In the heat exchanger design of the invention, the fins of the fin-and-tube assembly each have U-shaped, spaced-apart edges which define a fin surface of a given area confined between lateral boundaries spaced-apart by a distance that is smaller than the developed length of either side. This allows the fin-and-tube assembly to be made smaller both depthwise and lengthwise than would be possible using prior art rectangular fins.

According to one embodiment of the invention, the spacing and contour of these U-shaped edges are such that the fins are of crescent-shaped configuration, and according to another embodiment, the fins are more of a U-shaped configuration with rectangular corners. By using such fin configurations, more heat transfer surface is placed closer to the inlet of the radiator enclosure for greater natural draft than would be achieved for the same tubes carrying rectangular fins. Consequently, such improved heat transfer allows economical reductions in the number and size of the tubes.

While the invention basically contemplates fins with U-shaped edges, the artisan will appreciate an exact U-

shape is not essential and the edges can even be approximately V-shaped.

With the invention, the cabinet enclosure and fin-and-tube assembly can be made smaller for a given BTUH rating. Conversely, the same cabinet and fin-and-tube assembly gives a higher BTUH rating than in the prior art.

For a better understanding of the invention and its several advantages, reference should be had to the accompanying drawing and following detailed description pertaining to certain preferred embodiments of the invention.

BRIEF DESCRIPTION OF THE DRAWING

- 15 In the drawing:
 FIG. 1 is a perspective view, partly broken away, of a convection radiator equipped with a fin-and-tube heat exchange assembly constructed in accordance with a preferred embodiment of the invention.
- 20 FIG. 2 is a perspective view of the fin-and-tube assembly shown in FIG. 1 as seen removed from the radiator enclosure.
 FIG. 3 is a view of a typical fin used in the fin-and-tube assembly of FIG. 2.
- 25 FIG. 4 is a view of a different fin configuration that can be substituted for that shown in FIG. 3 to make a fin-and-tube assembly in accordance with another embodiment of the invention.

DESCRIPTION OF THE PREFERRED EMBODIMENTS OF THE INVENTION

In FIG. 1 there is shown a convection radiator 10 having an enclosure 11 within which is situated a fin-and-tube heat exchanger assembly 12, shown separately in FIG. 2.

Enclosure 11 defines an air flow path that extends from inlet opening 13 adjacent the floor 14, up past assembly 12 to outlet grill 15 at the top of enclosure 11.

Assembly 12 has a plurality of laterally spaced-apart heat exchanger tubes 16 disposed generally parallel at the same elevation plane above floor 14. At opposite ends, tubes 16 are connected to manifolds 17 which in turn are connected to pipes 18 that extend up through floor 14. To allow reasonable working space for making up the plumbing connections, pipes 18 are extended about seven inches above floor 14, and according to standard practice in the art, the connections of pipes 18 to manifolds 17 are made no lower than such height.

50 On tubes 16 are carried a multiplicity of transversely disposed fins 19, shown in detail by FIG. 3. To protect the fins 19 from handling damage, assembly 12 is laterally enclosed by a rectangular frame 20.

From FIG. 3 it can be noted that the fins 19 are crescent-shaped and in addition to holes 21 for insertion of tubes 16, each fin 19 has a pair of U-shaped edges 22 and 23 that are disposed in spaced-apart relation to define a fin 19 surface of a given area confined between lateral boundaries W1 and W2 spaced apart a distance smaller than the developed length of either one of the edges 22, 23.

Fin edges 22 and 23 are preferably located symmetrically with respect to the heat exchanger tubes 16, and the holes 21 are therefore placed equidistantly from the central line of symmetry W0.

Edges 22 and 23 are expediently circular arcs of the same radius R but with centers spaced-apart on line W0

by a distance h . Consequently, the edges 22 and 23 will be uniformly spaced apart by the distance h as measured parallel to line W0. This type of fin configuration is advantageous because it allows more heat transfer surface to be carried between lateral boundaries W1 and W2 than would be possible with rectangular fins (not shown) equal in width to the distance between W1 and W2, and equal in height to h . Furthermore, such configuration places a certain amount of heat transfer surface below the tubes 16, so that in a given size enclosure 11, greater output is obtained as compared to the same tubes 16 with rectangular fins, because of the increase in effective draft height, with the same total fin area.

In FIG. 4 there is shown a fin 25 having a somewhat different configuration and which can be substituted for the fin 19 in the manufacture of an assembly 12. Fin 25 has holes 26 located and sized for insertion of tubes 16, and a pair of U-shaped edges 27 and 28 that are uniformly spaced-apart as measured parallel to the central line of symmetry. Within given lateral boundaries the fin 25 can present somewhat more surface than the fin 19 configuration, because the rectangular corners 29 and 30 add area that would be lost if the edge 28 were to be cut along the arcuate continuation lines 31 (shown in phantom).

It should be noted that the fins 19, 25 are placed upon tubes 16 so that the convex edges 23, 28 respec-

tively are oriented toward the inlet side of the air flow, in order to maximize the induced draft by placing the effective heating surface further from the outlet grill 15.

5 The invention is readily adapted to meet the needs of a specific application, as will become obvious to the artisan from the description herein of a limited number of preferred embodiments of the invention.

What is claimed is:

- 10 1. A convection heat exchanger which comprises an enclosure adapted to rest upon an underlying base surface and having an inlet adjacent such base surface and an outlet at an elevation thereabove, said enclosure defining an airflow path extending from said inlet to said outlet, a plurality of laterally spaced-apart heat exchanger tubes disposed within said enclosure at an intermediate elevation above such base surface, and a multiplicity of transversely disposed similar fins carried by said tubes in symmetrically disposed relation thereto, said fins each having a pair of U-shaped, curved edges disposed in vertically spaced-apart relation to define a fin surface of a given area confined between lateral boundaries spaced-apart a distance smaller than the developed length of one of said edges.
- 15 2. A convection heat exchanger according to claim 1 wherein said fins have rectangular corners positioned in alignment with one another.
